OTHER PUBLICATIONS

A page from an Aug. 1992 brochure of Campbell Hausfeld Professional showing, *inter alia*, a Model VT6172 air compressor.

A page from a brochure of Emglo Products Corporation apparently dated Feb. 1993 showing several air compressors, admitted prior art.

Primary Examiner—Ralf Seifert
Attorney, Agent, or Firm—Quarles & Brady

[57] CLAIM

The ornamental design for an air compressor base assembly, as shown and described.

DESCRIPTION

FIG. 1 is a perspective view taken from the top, front and right side of an air compressor base assembly embodying our new design;

FIG. 2 is a top plan view thereof;

FIG. 3 is a front elevational view thereof;

FIG. 4 is a right side elevational view thereof; and,

FIG. 5 is a left side elevational view thereof.

The broken line representations in FIG. 2 of holes for an engine shaft and fuel line and in FIG. 3 of an engine and intake structures are for the purpose of illustration only and form no part of the claimed design.
